(57) **CLAIM**

The ornamental design for an air vent cover, as shown and described.

DESCRIPTION

FIG. 1 is a perspective view of an air vent cover showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a cross sectional view in the direction of 8-8 in FIG. 7;

FIG. 9 is a bottom view thereof;

FIG. 10 is another perspective view thereof;

FIG. 11 is another left side view thereof; and,

FIG. 12 is another front view thereof.

The broken lines and unshaded areas throughout the drawings depict portions of the air vent cover that form no part of the claimed design. All other broken lines shown in FIGS. 10-12 depict environmental subject matter that forms no part of the claimed design.
